UNITED STATES PATENT OFFICE.

GEORGE P. SHEFFIELD, OF ROCHESTER, NEW YORK, ASSIGNOR OF ONE-HALF TO LILIAN B. HOLLING, OF SAME PLACE.

THREADED COUPLING-BOLT.

SPECIFICATION forming part of Letters Patent No. 657,297, dated September 4, 1900.

Application filed June 6, 1900. Serial No. 19,306. (No model.)

To all whom it may concern:

Be it known that I, GEORGE P. SHEFFIELD, of Rochester, in the county of Monroe and State of New York, have invented a new and useful Improvement in Threaded Coupling-Bolts, which improvement is fully set forth in the following specification and shown in the accompanying drawings.

My invention is a threaded bolt belonging more particularly to the class commonly known and understood as "coupling-bolts," in parts, the same being hereinafter fully described and more particularly pointed out in the claims.

15 This bolt or device is in three parts—first, a threaded shaft or body; second, a detachable or removable thread-piece or thread to meet and coact with the thread of the shaft or body, and, third, a prismatic body in the 20 form, as to its exterior, of a screw-nut for the bolt adapted to receive an ordinary wrench for turning it and constructed to surround or inclose the thread-piece.

Referring to the drawings, Figure 1 is a 25 side elevation of the invention, parts being broken away and longitudinally sectioned along the axis of the bolt. Fig. 2 is an end view of the device seen as indicated by arrow in Fig. 1. Fig. 3 is a longitudinal axial 30 section of the thread-piece sectioned on the dotted line 3 3 in Fig. 2. Fig. 4 is a side elevation of the device, showing a different form of thread-piece, parts being longitudinally sectioned. Fig. 5 is an end view seen as indicated by arrow in Fig. 4. Fig. 6 is a side 35 elevation of the device, showing a round or cylindrical thread, parts being longitudinally sectioned. Fig. 7 is a side elevation of the threaded end of the bolt, the round or wire 40 threads being axially sectioned.

A, Figs. 1, 2, and 4, is the shaft or body of the bolt, which is of common form, provided with an ordinary head B. The bolt is formed with the ordinary V-thread *a* at one end, upon 45 which is fitted to turn a thread-piece *b*, Figs. 1, 2, and 3, formed internally with a thread *c* to fit and fill the thread *a* of the body A of the bolt. This thread-piece is adapted to be screwed onto or off of the body A like an ordinary threaded nut, and it may be made spiral, as shown in Figs. 1 and 3, or in other 50

forms, (shown in Figs. 4 and 6,) so as to be compressible to tightly press the body or shaft A. The thread-piece is conical or tapered on its exterior, the small end being toward the head B of the bolt, there being an independent or separate inclosing body C provided for controlling the thread-piece having a corresponding conical interior in which to receive the thread-piece, as shown. 60 The controlling-body C has a polygonal periphery—square, hexagonal, or other form—for the purpose of receiving an ordinary wrench for turning it. The exterior of the thread-piece and the interior of the controlling-body C have relative diameters, so that normally the thread-piece projects at its larger end from the body C, as shown. Now when the body C is turned against the opposing part D (of the machine or device to be 70 pressed or held by the bolt) the thread-piece *b* will be caused to travel toward the part D or be drawn into the tapered body C. This on account of the taper fit will cause the yielding or compressible thread-piece to 75 firmly press the body A, tightening it thereon ever more firmly as the part C is turned by the wrench.

In the form shown in Figs. 4 and 5 the only change is in the construction of the thread-piece *d*. Instead of being a spiral, as shown at *b*, Fig. 1, it is a simple band, tapered on its exterior to fit the controlling-body C and formed with a longitudinal slit *g*, so as to be compressible, as in the spiral form. As the 85 controlling-body C is turned against the part D the thread-piece *d* will be drawn into the tapered body C and tightened with great firmness upon the shaft A.

As shown in Figs. 6 and 7, the body or shaft 90 A' is formed with a spiral thread *f*, semicircular in cross-section instead of V-shaped, the thread-piece or thread *e* being a body, as wire, cylindrical in cross-section, wound in said semicircular spirals. The outer surface 95 of this wire spiral is tapered, as in the other cases, to receive the internally-tapered controlling-body C, the wire thread being drawn into the body C as the latter is turned.

The bearing of the body C against the outer 100 surface of the thread-piece, in either form shown, being farther out from the axis of the

bolt than the bearing of the thread-piece against the body A of the bolt, the tendency is to cause the thread-piece to turn upon the bolt rather than the body C to turn upon the thread-piece. If, however, there should be in any case a tendency of the body C to turn upon the thread-piece, said body C may be internally longitudinally corrugated, as shown at h in Fig. 2, or other simple and well-known means may be provided to cause the controlling-body and the thread-piece to turn together; but the former having the advantage of leverage over the thread-piece, as above stated, will tend to cause the thread-piece to move with it when turned, as stated.

15 What I claim as my invention is—

1. A threaded bolt, in combination with an independent or detachable spiral thread-piece longitudinally compressible, and a detachable body controlling and inclosing the thread-piece, the contiguous surfaces of the

thread-piece and controlling-body being tapered, substantially as and for the purpose specified.

2. The combination with a threaded bolt, 25 of a thread-piece of spirally-wound wire tapered and longitudinally compressible, and fitted to the threads of the bolt to project beyond the periphery of the bolt, and a separate body for inclosing and controlling the 30 thread-piece, said body having a tapered opening corresponding to the taper of the thread-piece and the whole adapted to serve substantially as herein shown and described.

In witness whereof I have hereunto set my 35 hand, this 4th day of June, 1900, in the presence of two subscribing witnesses.

GEORGE P. SHEFFIELD.
